W. H. LAZARUS,
CAN OR CONTAINER,
APPLICATION FILED MAR. 27, 1919.

1,328,881.

Patented Jan. 27, 1920.

FIG. 1

FIG. 2

INVENTOR

Wiliam H. Lazarus,

By Ralph Koenig ATTORNEY.

UNITED STATES PATENT OFFICE.

WILLIS H. LAZARUS, OF ST. LOUIS, MISSOURI, ASSIGNOR TO S. PFEIFFER MANUFACTURING COMPANY, OF ST. LOUIS, MISSOURI, A CORPORATION OF MISSOURI.

CAN OR CONTAINER.

1,328,881.

Specification of Letters Patent. Patented Jan. 27, 1920.

Application filed March 27, 1919. Serial No. 285,442.

To all whom it may concern:

Be it known that I, WILLIS H. LAZARUS, a citizen of the United States, residing at the city of St. Louis, State of Missouri, have 5 invented a certain new and useful Improvement in Cans or Containers, of which the following is a specification, reference being had to the accompanying drawing, forming a part thereof.

10 This invention relates generally to containers and, more particularly, to a certain new and useful improvement in cans.

The principal object of my present invention is to provide a simple, inexpensive, 15 and efficient can or container having a fixed spout-containing and concealing chamber or compartment formed within the can-body, and a movable spout, the spout being adapted to occupy such chamber or compartment and 20 the spout-opening or neck of the can being closed by a cap or other closure when the can is not in use, whereby the can may be conveniently handled and compactly stored in shipment or in trade, and the spout being 25 readily accessible on removal of the can-closure and facilely threaded or otherwise manipulated to full operative or working position relatively to the can or container when the can or container is to be used.

30 With the above and other objects in view, my invention resides in the novel features of form, construction, arrangement, and combination of parts hereinafter described and afterward pointed out in the claims.

35 In the accompanying drawing,

Figure 1 is a vertical sectional view of a can, fragmentarily shown, constructed in accordance with and embodying my invention, the can being closed and the spout 40 occupying its containing chamber; and

Fig. 2 is a similar view of the can as when in use, the spout being in operative or working position relatively to the can.

Referring to the said drawing, in which 45 like reference characters refer to the same parts throughout the several views, 1 indicates a suitable can, shown only fragmentarily for purposes of illustration, provided or formed at its top with an upstanding neck 2 spun, crimped, or otherwise provided circumferentially with threads 3 and bent inwardly or inturned at its upper end to provide an annular flange 4.

Disposed partly within the neck 2 and 55 partly within the can-body 1, is a tubular

member 5 adapted to provide the spout-containing chamber or compartment of the can. This member 5, throughout the upper portion of its length, is spun, crimped, or otherwise provided circumferentially with 60 threads 6, and at its upper end is bent outwardly to provide an annular flange 7, the member 5 being supported and preferably soldered or otherwise fixed at its flange 7 upon and to the flange 4 of the can-neck 2. 65 Throughout the remaining portion of its length, the member 5 is preferably smooth and plain and at its lower end is inturned, as at 8, to provide a seat or support for a coiled spring or other suitable elastic or resilient member 9 disposed preferably loosely within the chamber or compartment so provided or formed by the member 5.

Also disposed within the tube or chamber 5 and upon the spring or other member 9, 75 is a suitable ring or gasket 10; and also loosely disposed within the tube or chamber 5 to rest upon the gasket 10, when the can is not in use, is a tapering spout 11 having a suitably enlarged and circumferentially 80 threaded non-tapering lower portion or extension 12 of a diameter to fit and threadedly engage the upper threaded portion 6 of the tube or chamber 5.

When the can is not in use, as, for instance, 85 during shipment or storage, the spout 11 is adapted to occupy the chamber or compartment 5, as illustrated in Fig. 1, the spring 9 being correspondingly under compression, and the spout being entirely concealed from 90 view and held in such described position and the can, and its chamber 5 and spout 11 being tightly sealed against leakage by a preferably cork-containing cap or other suitable closure 13 adapted, as shown, to engage the 95 threaded neck 2 of the can. When the can is to be used, the cap or closure 13 is removed from the can, whereupon the spout 11, under the expansion of spring 9, will be resiliently elevated to a position relatively to 100 the upper end of the chamber 5, as indicated by dotted lines in Fig. 2, to be conveniently engaged by the user and then readily and easily threaded at its portion or extension 12 into engagement with the threaded portion 6 of tube or chamber 5 and so manipulated to full operative or working position relatively to the can, as illustrated in Fig. 2.

With the spout 11 in such described, full operative or working position, the oil or 11

other fluid contained within the can finds ready flow and exist discharge from the can without leakage, when the can is tilted, as is usual, through the open lower end of 5 the tube or chamber 5, the chamber 5, and the spout, 11, and to facilitate such flow, especially when the can is partly empty, I preferably, provide the chamber or tube 5 with one or more side intake-ports or apertures, as at 14.

10 I am aware that minor changes in the form, construction, arrangement, and combination of the several parts of my new can may be made and substituted for those herein 15 shown and described without departing from the nature and principle of my invention.

Having thus described my invention, what I claim and desire to secure by Letters Patent is:

20 1. In combination with a container, a tubular spout-containing chamber disposed within, and having communication with the interior of, the container, the upper portion 25 of the wall of the chamber having threads, and a tapering spout having an enlarged threaded extension at its lower end, the spout and its extension being adapted to loosely fit within and occupy the chamber 30 when the container is not in use and being movable outwardly relatively to the container and chamber to provide a nozzle-outlet for the container when the container is in use, the spout, when in such latter position, 35 having threaded supporting engagement at its said extension with the threaded upper portion of the wall of the chamber.

2. In combination with a container having an upstanding neck, a tubular member fixed 10 to the neck and having a threaded upper portion disposed within the neck and a smooth lower portion disposed within the body of the container, said member having communication with the interior of the can 15 and providing a spout-containing chamber,

and a tapering spout having a non-tapering enlarged threaded extension at its lower end, the spout and its extension being adapted to fit loosely within and occupy the chamber when the container is not in use and being 50 movable outwardly relatively to the container and chamber to provide a nozzle-outlet for the container when the container is in use, the spout, when in such latter position, having threaded supporting engagement 55 at its said extension with the threaded upper portion of the chamber.

3. In combination with a container having an upstanding neck, a tubular member fixed to the neck and having a threaded upper portion disposed within the neck and a smooth lower portion disposed within the body of the container, said member having communication with the interior of the container and being flanged inwardly to provide a seat at its lower end, a tapering spout having a non-tapering enlarged threaded extension at its lower end, the spout and its extension being disposed for movement relatively to the container and said member and adapted to fit loosely within said member when the container is not in use, a cap adapted for engagement with the neck to provide a closure for the neck and for the upper end of said member when the container is not in 70 use, and a spring disposed within said member and upon said seat for yieldingly moving the spout and its said extension outwardly relatively to the container and said member on removal of the cap, the spout, when so moved outwardly, being adapted to provide a nozzle-outlet for the container and when in such position having threaded supporting engagement at its said extension with the threaded upper portion of said 75 member.

In testimony whereof, I have signed my name to this specification.

WILLIS H. LAZARUS.
